UNITED STATES PATENT OFFICE

2,265,650

DUPLEX PUMPING APPARATUS

William H. Lannert, Chicago, Ill., assignor to
 Chicago Pump Company, Chicago, Ill., a corporation of Illinois

Application October 26, 1939, Serial No. 301,386

9 Claims. (Cl. 103—3)

This invention relates to duplex pumping apparatus and in its present form it has been designed for ejecting sewage. Usually a single inlet pipe or conduit is provided for the two pumps of the apparatus, which inlet pipe connects through a fitting with both pumps. Heretofore it has been found that paper, rags, fibrous and other solids collected in the fitting and clogged the passages therethrough, and one of the objects of the present invention is to eliminate clogging of the fitting.

Another object is to provide a duplex pumping apparatus in which rags, papers, fibrous and other solids are passed freely to certain strainers disposed in the discharge lines of the pumps, which strainers prevent solids from entering the pumps and interfering with their operation.

Ordinarily the pumps are operated alternately to eject sewage from a basin, and either one of the pumps is usually at rest. During the operation of the running pump it pumps liquids back through the strainer associated therewith, thereby flushing it and discharging the collected solids along with the liquids.

Another object is to provide a fitting of novel construction wherein the liquids which enter the fitting wash all of the solids out of the fitting, thereby preventing clogging thereof.

Another object is to provide an inlet fitting with a chamber having a bottom of concave or other suitably shaped contour, which chamber connects at places above the bottom thereof with two hollow branches that communicate with the discharge pipes of the pumps, whereby liquids discharging upon the bottom of the chamber, flow upward therein and spill into the two branches, or one of them, and carry away the solids, thus preventing clogging of the fitting.

With these and other objects and advantages in view, this invention consists in the several novel features hereinafter fully set forth and claimed.

The invention is clearly illustrated in the drawing accompanying this specification, in which:

Fig. 1 is a side elevation of a duplex pumping apparatus embodying a simple form of the invention, and showing the same applied to a basin which is illustrated in vertical section;

Fig. 2 is an elevation of the apparatus looking in the direction of the arrow 2 in Fig. 1, and showing the basin in vertical section;

Fig. 3 is a detail elevation of one embodiment of the fitting upon an enlarged scale, looking in the direction of the arrow 3 in Fig. 1.

Fig. 4 is a detail vertical cross section taken on the line 4—4 of Fig. 3, and

Fig. 5 is a vertical cross section taken along the irregular dotted line 5—5 of Fig. 4.

5 Referring to said drawing, which illustrates one embodiment of the invention, the reference character 6 designates a receptacle in which the duplex pumping apparatus is contained. In accordance with the application of the invention illustrated, the receptacle is in the nature of a basin, although it may take the form of a dry pit associated with a basin, as is well understood.

10 Duplex pumps 7, 8, preferably of the centrifugal type, are supported adjacent the bottom of the receptacle by hanger pipes 9, which are carried by the cover 10 for the receptacle. Electric motors 11, 12 are mounted on motor bases 13, 14, supported by the cover 10, and their motor shafts (not shown) are connected to the impeller shafts 15 of the pumps in the usual manner well known to those skilled in the art to which this invention pertains.

15 The suction inlet of each pump is through a suction plate 16 located at the bottom of each pump case, and the discharge is through a volute 16a, to which is connected a strainer 17 of conventional form, the upper end of which is connected by a T fitting 18 with a discharge pipe 19. The discharge pipes usually lead up through the cover and are connected by suitable fittings to discharge pipes (not shown) which carry away the ejected sewage. When the pumping apparatus is used in a dry pit, the suction inlets of the pumps are connected by suitable pipes or conduits with an associated basin as is well understood.

20 An inlet pipe or conduit 20, common to both pumps, leads from the source of supply to the receptacle 6, and its end is connected to a fitting 21 bolted or otherwise fastened to a wall of the receptacle. Desirably the fitting is composed of a single cored casting, and is formed with a bolting flange 22 on one side, bolted to a wall of the receptacle and having a hub 23 on its outer side containing an inlet opening 25a, in which the end of the inlet pipe is received. Any suitable form of joint may be provided between the inlet pipe and hub of the fitting.

25 The wall 24 of the main body of the fitting provides a chamber 25 having a bottom, whose wall 27 is desirably of concave or other desirable shape, merging into the upright wall of the main body portion. Desirably the wall 24 of the body

is curved and merges into the bolting flange 22 and hub 23.

In opposite sides of the wall 24 above its bottom, two outlet openings, 28, are formed, and extending from the two sides of the wall 24 around the openings 28 are two hollow branches 29 that lead to a bolting flange 30 through which the branches open out as at 31.

From an inspection of Fig. 5 it will be seen that the chamber 25 communicates with the inlet opening 25a of the fitting near the upper end of the chamber, and that the latter communicates with the two branches at places above the bottom of the chamber through the openings 28. Liquids spilling into the chamber fall upon the bottom thereof, carrying with them any solids that may accompany the liquids. In their passage to either branch 29, the liquids spill over the edges that define the lower edges of the openings 28, carrying any solids up and over said edges with them. Rags, paper, strings, fibrous and other solids are thereby washed out of the bottom portion of the chamber and carried down the branch through which the liquids are flowing.

Each outlet 31 of the branches is connected to an associated discharge pipe 19 by suitable connections, whereby the incoming liquids and solids may pass to the discharge pipe and through the strainer, where the solids are intercepted, and the strained liquids may flow through the pump and discharge therefrom through its suction inlet, into the basin.

As shown, the connections just mentioned may comprise gate valves 32, one for each branch of the fitting, and bolted to the bolting flange 30 of the fitting, pipes or other conduits 33 connected to the gate valves and check valves 34, one connecting each pipe 33 with one of the T fittings 18. The check valves open in the direction of flow through the pipes or other conduits 33.

Desirably a strainer 35 is secured to the open top of the fitting, through which liquids may escape in the event that the liquid enters the receptacle faster than one pump can discharge it therefrom.

The switches for the motors may be manually operated, if desired, to run the pumps alternately, but it is preferred to have their operation controlled automatically. For this reason suitable means are provided for starting and stopping the pump motors and for starting them in alternate sequence. The means shown comprises float operated electric switches 36, of which the floats 37 are located in the receptacle or in the basin, if a separate basin is used to receive the liquids and from which they are ejected. To the floats are secured float rods 38 which are guided in sleeves 39 and have buttons upon their upper ends, for tripping the switches, and suitable alternating means 40 is provided whereby the pump motors are started alternately. Various forms of alternating devices may be used, an example of which is that shown and described in the A. C. Durdin, Jr. Letters Patent No. 1,666,873, dated April 17, 1928, for a Duplex pumping apparatus.

In this apparatus one float mechanism, together with its alternating device, operates to start one pump motor when the liquid reaches a pre-determined high level and stops the motor when the liquid reaches a low level, and when the liquid again reaches the high level the other float mechanism starts the other pump motor and stops it when the liquid reaches the low level. In case the liquid accumulates faster than one pump can eject it, the idle motor is then cut in

and both pumps act to eject the liquid. When the low level is again reached, both pumps are stopped.

In operation and with the receptacle or basin 5 empty, liquids enter the fitting, fall upon the bottom of the chamber and spill into the two branches, carrying with them any accompanying solids; thence through the connections to the discharge pipes, down through the strain 10 ers, where the solids are intercepted, and the strained liquids pass through the volute discharge ends of the pumps, into the latter and out through the suction inlets thereof, into the receptacle, or into a separate basin, if one is used.

15 When the float mechanism which is set to operate first, is raised by the accumulated liquids which have risen to the pre-determined level, it trips the electric switch for the motor which is to start first. The pump of that motor starts, thereby discharging liquid from the basin through the strainer associated with it, the liquid carrying the collected solids with it and discharging through the associated discharge pipe. Pressure being set up in the discharge pipe, the check 20 valve associated therewith closes, preventing back flow through the connections with the fitting. Liquid which continues to flow into the fitting from the inlet pipe, flows through the branch of the fitting that connects with the idle pump, through the associated connecting pipe, check 25 valve and T fitting, through the strainer, and through the idle pump into the receptacle as has just been explained.

With one pump in operation liquids may 30 continue to flow into the fitting from the inlet pipe and pass through both branches and both connections, 33, but inasmuch as the check valve in one connection to the discharge pipe of the pump which is in operation is closed, that branch from 35 the fitting will fill, and then the flow will be through the other branch to and through the connections 33, strainer and idle pump and into the receptacle or basin. Rags, paper, string and other solids carried in the liquids fall into the 40 concave bottom of the chamber as indicated by the arrows in Figs. 4 and 5, and are washed into the branch leading to the idle pump. If the flow is very heavy, a portion of the stream will flow directly from the inlet to the outlet 28 of the 45 branch leading to the idle pump.

The apparatus above described is especially 50 adapted for handling sewage, but its use is not limited thereto as it may be used for pumping liquids containing solids.

I claim as new and desire to secure by Letters 55 Patent:

1. In pumping apparatus which employs an inlet pipe, duplex motor driven pumps and discharge pipes therefor, a non-clogging inlet fitting having upright and bottom chamber walls providing an upright chamber having a bottom, and having an inlet opening adjacent its upper end connected to said inlet pipe, said fitting having other walls providing two hollow branches which 60 open from the chamber at places below the inlet opening and above the bottom of the chamber, said branches being connected respectively to said discharge pipes.

2. In pumping apparatus which employs duplex motor driven pumps, a common inlet pipe therefor, and discharge pipes therefor, a non-clogging inlet fitting comprising an upright wall and a bottom wall providing an upright chamber having an inlet opening disposed above its bottom and communicating with said inlet pipe,

said fitting having also other walls providing two hollow branches which extend from the sides of the upright wall and are connected respectively to said discharge pipes, each branch opening at one end to said chamber below the inlet opening with the lower edge of the branch opening to the chamber above the bottom of the chamber to leave a pocket therein below the lower edges of the branch openings to the chamber.

3. In pumping apparatus which employs duplex motor driven pumps, a common inlet pipe therefor, and discharge pipes therefor, a non-clogging inlet fitting comprising an upright wall and a concave bottom wall merging into the upright wall, said walls providing an upright chamber having an inlet opening disposed above its concave bottom and communicating with said inlet pipe, said fitting having also other walls providing two hollow branches connected respectively to said discharge pipes, which branches extend from the sides of the upright wall, each branch opening at one end to said chamber below the inlet opening with its lower edge disposed above the concave bottom of the chamber to leave a pocket therein below the lower edges of the branch openings to the chamber.

4. In duplex pumping apparatus, a non-clogging inlet fitting consisting of a cored casting comprising an upright wall and a bottom wall which provide an upright chamber having an inlet opening adjacent its upper end and a bottom located therebelow, the fitting being formed with other walls providing hollow branches which open at one end to said chamber through openings in its upright wall, the lower edges of the openings from the chamber to the branches being located above the bottom of the chamber to leave a pocket below said lower edges, and said branches having outlets at their other ends.

5. In duplex pumping apparatus, a non-clogging inlet fitting consisting of a cored casting comprising an upright wall and a concave bottom wall merging into the upright wall, said walls providing an upright chamber having an inlet opening adjacent its upper end and a concave bottom located therebelow, said casting having other walls providing hollow branches which open at one end to said chamber through openings in its side wall, disposed above the concave bottom wall, said branches having outlets at their other ends.

6. A fitting consisting of a hollow casting comprising an upright wall and a concave bottom wall forming an upright chamber having an inlet opening adjacent its upper end and a concave bottom, said casting having other walls providing two hollow branches which extend from

the upright chamber wall and open to the chamber below its inlet opening, with the lower edges of the branch openings disposed above the concave bottom of the chamber, said branches having outlets at their other ends and bolting flanges, one merging into the upright chamber wall and having the inlet opening therein and the other flange merging into the outlet ends of the branches.

7. A fitting consisting of a hollow body comprising an upright wall and a concave bottom wall forming an upright chamber having a concave bottom, there being an inlet opening adjacent the upper end of the chamber and two outlet openings through the upright chamber wall disposed below the inlet opening and above the concave bottom, whereby liquids falling upon the concave bottom spill over the edges of said outlet openings, said fitting having other walls extending from said upright chamber wall around said outlet openings and provide hollow outlet branches into which the liquids spill from said concave bottom of the chamber.

8. A fitting consisting of a cored casting comprising an upright wall and a concave bottom wall which provide an upright chamber having a concave bottom, there being an inlet opening to the chamber adjacent its upper end and two outlet openings which open through the upright chamber wall below the inlet opening and above the concave bottom of the chamber, said fitting having other walls providing two downwardly directed hollow branches, said last mentioned walls joining the upright chamber wall around said outlet openings.

9. In duplex pumping apparatus which employs duplex motor driven pumps, a common inlet pipe therefor and discharge pipes therefor, a non-clogging inlet fitting comprising an upright wall and a concave bottom wall merging into the upright wall, said walls providing an upright chamber having a concave bottom, other walls extending from two opposite sides of the upright wall and providing two hollow branches, each branch leading from the chamber through an opening in its upright wall with the lower edge of each opening located above the concave bottom of the chamber, whereby to leave a pocket therein below the lower edges of the branch openings to the chamber, said upright wall having an inlet adjacent its upper end disposed above the branch openings to the chamber and connected with the inlet pipe, and the other ends of the branches having connections respectively with the discharge pipes.

WILLIAM H. LANNERT.
